REGENERATIVE STEAM AND WATER
MIXING DEVICE

Harry H. Decker, Chicago, Ill., assignor to The
Lathrop-Paulson Company, Chicago, Ill., a cor-
poration of Illinois

Application October 15, 1938, Serial No. 235,288

3 Claims. (Cl. 261—76)

This invention relates to a regenerative type of steam and water mixing device. It is particularly useful in connection with can washing machines for providing a hot sterile rinse.

5 In mixing guns or devices of the type employing steam and water heretofore used, considerable difficulty has been experienced with "breaking", the tendency of the steam to pass through the apparatus without picking up water. It has been 10 further been found that an excessive quantity of steam is employed.

An object of the present invention is to provide mechanism whereby the tendency of the gun to "break" is overcome and in which a smaller 15 amount of steam is employed for the same work. A further object is to provide a gun or mixing device in which very accurate control of the operation is made possible.

A still further object is to provide means where- 20 by a portion of the heated water leaving the mixing chamber is utilized for heating the incoming cold water so that there is supplied to the steam inlet a body of warm water which greatly facilitates the mixing of the steam and water. Other 25 specific objects and advantages will appear as the specification proceeds.

The invention is illustrated in a preferred embodiment by the accompanying drawing, in which—

30 Figure 1 is a side view in elevation of apparatus embodying my invention; and Fig. 2, a similar view, the main parts of the apparatus being shown in longitudinal section.

In the illustration given, A designates a mixing 35 apparatus; B, a by-pass or recycling device; and C, a spray nozzle.

The apparatus A, in the illustration given, includes a steam inlet elbow 10 to which is threadedly secured a steam nozzle 11. The steam nozzle 40 threadedly engages a fitting 12 with which is integrally formed a water inlet bulb or cylinder 13. The member 13 is interiorly threaded on its upper end to receive a mixing tube 14. The member 12 is supported within an interiorly 45 threaded fitting 15 which, in turn, is threadedly connected to a hollow water inlet cylinder 16. The cylinder 16 surrounds the bulb 13 and communication between the two is established through ports 17. A nut 18 seals the lower end 50 of the fittings 12 and 15.

Surrounding the upper portion of the mixing tube 14 is a water intake 19, the upper end of which is sealed by nut 20. The members 19 and 16 are threadedly connected by a hollow nipple 55 21. Thus there is provided a continuous water

chamber leading from the intake 19 downwardly through the nipple 21, water inlet fitting 16, through ports 17, into the interior of the cylinder 13.

The upper end of the mixing pipe 14 threadedly engages the two-way fitting 22. From the fitting 22 the liquid may pass through the return pipe B back to water inlet fitting 16, or it may pass in the other direction through pipe 23 to the nozzle C.

The recycling device B includes a nipple 24, a bend 25, a return pipe 26, an adjustment fitting 27, a nipple 28, and a reducer fitting 29. In the fitting 27 is threadedly secured a valve head 30 which engages the opening provided by the nipple 28 and serves to enlarge or diminish the opening. The fitting 27 is sealed on the outer side by the member 31. The outer end of the valve member 30 is provided with an hexagonal head 32.

The spray nozzle C may be of any suitable type. 20 The one illustrated is employed for directing a stream of hot water into the open mouth of a can to provide a sterile rinse therefor. The dimensions of the nozzle are such that not all 25 of the water heated in pipe 14 can be discharged therefrom and a portion thereof is thus caused to be recycled through the conduit B.

Operation

In the operation of the apparatus, steam enters 30 the elbow 10 and enters through nozzle 11 into the cylinder 13 from whence it passes into the mixing chamber 14. Cold water enters through the intake fitting 19 and passes around the chamber 14 and in contact therewith downwardly 35 through nipple 21 and into the water inlet fitting 16. From the water inlet fitting 16, the water passes through ports 17 into the member 13 where it meets the steam and is carried into the mixing chamber 14. The heated water leaving the mixing chamber is divided into two streams, one leaving through pipe 23 to the spray nozzle C and the other returning through pipes 24, 25, 26, 27 and 28 to the water inlet fitting 16. The returned heated water mixes with the cold water 40 in the fitting 16 and provides a warm water body about the cylinder 13 and about the steam nozzle 11. It will also be noted that the incoming cold water through pipe 19 contacts the heated pipe 14 and is pre-warmed by this contact before it reaches fitting 16. By this arrangement, the pre-heated water is found to mix readily with the steam and to provide continuous operation in which the steam and water are effectively mixed. The operation is controlled to provide a nice 45 50 55

relation of the streams through the valve head 30, the hexagonal head 32 of which may be readily manipulated.

With the type of gun heretofore in use, in order to maintain a proper flow of hot water at 195° to 200°, it was necessary to open the steam valve fully and then get the desired temperature by cutting down the stream of water. With the present regenerative type of gun or mixer, the operation is just the reverse. The amount of water needed is controlled by the opening in the spray head and the valve 30, and it is only necessary to open the steam valve controlling the elbow 10 a short distance, never more than one-half turn. Through the recirculation of the hot water, the steam consumption is considerably reduced while at the same time the tendency for the gun to "break" is substantially eliminated.

In the foregoing description, I have set forth specific details in order to illustrate the one method of operation of the invention. It will be understood, however, that such details may be modified greatly by those skilled in the art while still utilizing the spirit of my invention.

The foregoing detailed description has been given for clearness of understanding only, and no unnecessary limitations should be understood therefrom, but the appended claims should be construed as broadly as permissible, in view of the prior art.

I claim:

1. A mixing device of the class described com-

prising a steam and water mixing chamber, a steam nozzle communicating with one end of said chamber, a water inlet chamber communicating with said steam inlet, and a discharge conduit communicating with the discharge end of said steam and water mixing chamber and leading in one direction to a nozzle and in the other direction to a return conduit, said return conduit communicating with the chamber about said steam nozzle. 5

2. A mixing device of the class described comprising a steam and water mixing chamber, a steam nozzle communicating with one end of said chamber, a water inlet chamber communicating with said steam inlet, a discharge conduit 15 communicating with the discharge end of said steam and water mixing chamber and leading in one direction to a nozzle and in the other direction to a return conduit, said return conduit communicating with the chamber about said steam nozzle, and valve means for controlling the flow through said return conduit. 10

3. In apparatus of the class set forth, a steam and water mixing chamber, inlet means for introducing steam into one end thereof, means 25 for introducing water adjacent the point of introduction of said steam, and a discharge conduit communicating with said chamber and leading in one direction to an outlet and in the other direction to a return conduit, said return 30 conduit communicating with said chamber.

HARRY H. DECKER.
